(57) **CLAIM**

The ornamental design for a computer mouse, as shown and described.

DESCRIPTION

FIG. 1 is a right rear perspective view of a computer mouse showing my new design.

FIG. 2 is a left rear view thereof.

FIG. 3 is a right front perspective view thereof.

FIG. 4 is a left front perspective view thereof.

FIG. 5 is a right side view thereof.

FIG. 6 is a left side view thereof.

FIG. 7 is a front view thereof.

FIG. 8 is a rear view thereof.

FIG. 9 is a top view thereof; and,

FIG. 10 is a bottom view thereof. The broken lines that show the features on the bottom form no part of my design. A computer mouse for pointer control.
